DOUBLE ACTION HAIR PIN

Wilbur D. Williams, Pancoastburg, Ohio

Application May 24, 1955, Serial No. 510,660

2 Claims. (Cl. 132—52)

The present invention relates to certain new and useful improvements in a hair pin which may be classed as falling in the general category of so-called bobby pins, the same being structurally distinct in that instead of providing a single pair of grips or jaws, two pairs of jaws are provided.

In carrying out the inventive concept and reducing to practice a preferred embodiment thereof, the resultant construction provides a structurally unique pin which will effectually hold pin curls and hold hair in any position better, it is believed, than any competitive or analogous pin construction in the same field of endeavor or size, the construction being such that it may be economically produced and sold at a price in competition with the simpler two-jaw bobby pins currently in vogue.

Another object of the invention is to structurally, functionally and otherwise improve upon similarly constructed and performing hair pins and, in doing so, to effectually serve the expected or ordinary manufacturing requirements of manufacturers, competitive sales requirements of retailers, and long anticipated needs of hair dressers and users.

Briefly summarized, the invention in a preferred embodiment thereof is characterized by two complementary or companion units, one a J-shaped primary unit embodying a long limb which is substantially linearly straight, a short limb parallel to but spaced from the long limb and a curvate bight portion joining said limbs together, that portion of said long limb extending beyond the free end of the short limb constituting a first jaw, and an auxiliary unit complementary to said primary unit, and pivotally mounted on said short arm and having a portion projecting beyond the latter and opposed to said first jaw and providing a second jaw.

More explicitly, the invention has to do with a primary unit which is J-shaped and characterized by a long arm which is linearly straight, a short arm or limb approximately parallel to but spaced from the long limb and joined thereto by a resilient curvate bight portion, that portion of the long arm which extends beyond what may be said to be the free end of the short limb or arm constituting a first jaw, there being an auxiliary unit complementary to the primary unit and embodying a relatively long approximately straight arm freely hinged between its ends on the free end of said short arm and having an approximate half-portion projecting beyond said free end and opposed to said first jaw and providing a second jaw.

Other objects, features and advantages will become more readily apparent from the following description and the accompanying sheet of illustrative drawings.

In the drawings:

Figure 1 is a perspective view of a duplex or double acting hair pin constructed in accordance with the principles of the present invention;

Figure 2 is a central longitudinal sectional view taken on the plane of the line 2—2 of Figure 1 looking in the direction of the arrows and on a larger scale and also showing the main or principal outer jaws closed and

2

illustrating, in phantom or dotted lines, how these jaws are sprung apart to assume what is identified as the open position thereof;

Figure 3 is a cross-section on the vertical line 3—3 of Figure 2;

Figure 4 is an edge elevation based on Figure 2 and showing how the respective jaw portions of the respective units are approximately parallel to provide the combined action of the respective pairs or sets of jaws when both pairs of jaws are approximately the same distance apart; and

Figure 5 is a similar edge elevation wherein it may be said that the outer jaws are close together and the inner jaws are spaced apart when the bulk of the hair is in

15 what may be called the bight or rear portion of the pin.

Referring now to the drawings with the aid of reference numerals and wherein the latter designate like parts throughout the views of the drawings, it will be seen that the aforementioned primary J-shaped unit or part

20 is denoted by the numeral 8 while the complementary secondary unit is denoted by the numeral 10. Unit 8 is characterized by a substantially linearly straight long arm 12, a resilient curvate bight portion 14 and a relatively short complementary limb 16 which is approximately one-half the length of the limb 12. The short limb terminates in a curl forming an assembling and hinging eye 18. The left hand end portion of limb 12 extending beyond the eye provides one of the outer or principal jaws, this being here denoted by the numeral 20. The

30 inner half-portion 22 provides one of the inward or so-called inner jaws. The complementary unit 10 is here described as an elongate arm and it is slightly longer than the arm 12. It is treated here as divided into half-portions; namely, an outer half-portion 24 which extends

35 beyond the eye 18 and constitutes the remaining one of the primary pair of jaws. In other words, these two jaws are identified as the outer jaws 20 and 24. This

40 jaw 24 is preferably kinked or suitably crimped and the free end or terminal is flared outwardly as at 26, much in the customary manner of forming one of the spring clamping jaws of an ordinary bobby pin. The intermediate portion of this arm has inturned bends which constitute assembling and hinging hooks 28, and these are hingedly connected with the eye 18. The half-portion 30

45 which extends between the short arm 16 and portion 22 of the long arm provides another jaw. Thus, the inner jaws are 22 and 30. The free end portion 32 of this half-portion of the arm is formed with a slot 34 which is operatively engaged and cooperates with the bight portion 14. Thus, a duplex bobby-type hair pin is provided.

In practice, the unique readily clampable end portion is placed in the hair of the user with the hair between the terminal portions of the outer grips or jaws 20 and 24 the same as would be the situation in using any ordinary bobby pin. The bulk of the hair is generally between

50 30 and 22 which causes the movable jaw or half-portion 30 to tilt to the angled position shown, for example, in Figure 5 and to create more pressure at the outer free ends of the jaws 20 and 24. The unit 10 is held or suspended by way of the hinging eye and assembling hooks 28 and therefore, the respective pairs or sets of jaws 20 and 24 to the left of the drawings and 30 and 22 to the

55 right in the drawings are dependent upon the particular hair clamping situation at hand. In Figure 2, the parts are 60 in what may be said to be the closed position when they are not in use. In Figure 5, we see the position when the bulk is in the rear of the clamp, and in Figure 4, we see the position of parts when equal amounts are at the front and rear ends between the respective pairs of jaws.

65 70 The foregoing is considered as illustrative only of the principles of the invention. Further, since numerous modifications and changes will readily occur to those

skilled in the art, it is not desired to limit the invention to the exact construction and operation shown and described, and accordingly, all suitable modifications and equivalents may be resorted to, falling within the scope of the invention as claimed.

What is claimed as new is as follows:

1. A hair pin comprising a substantially J-shaped primary unit embodying a long limb which is substantially linearly straight, a short limb parallel to but spaced from the long limb and a curvate bight portion joining said limbs together, that portion of said long limb extending beyond the free end of the short limb constituting a first jaw, and an auxiliary unit complementary to said primary unit, and embodying a relatively long approximately straight arm freely hinged between its ends on the free end of said short arm and having an approximate half-

10

15

portion projecting beyond said free end and opposed to said first jaw and providing a second jaw, the other half-portion being situated and swingable between said short and long limbs and cooperating with the latter and providing a second pair of jaws.

2. The structure defined in claim 1 and wherein that end of the last named half-portion is slotted and slidably engaged with said bight portion.
